UNITED STATES PATENT OFFICE.

FRANK L. HARMON, OF BEVERLY, MASSACHUSETTS, ASSIGNOR TO SINGER MANUFACTURING COMPANY, OF ELIZABETH, NEW JERSEY, A CORPORATION OF NEW JERSEY.

VARIABLE-FEED MECHANISM FOR EYELETING AND OTHER MACHINES.

1,260,260.

Specification of Letters Patent. Patented Mar. 19, 1918.

Application filed May 12, 1914. Serial No. 837,985.

To all whom it may concern:

Be it known that I, FRANK L. HARMON, a citizen of the United States, and resident of Beverly, county of Essex, Commonwealth of Massachusetts, have invented 5 an Improvement in Variable-Feed Mechanisms for Eyeleting and other Machines, of which the following description, in connection with the accompanying drawings, 10 is a specification, like characters on the drawings representing like parts in each of the several views.

This invention relates to feed mechanisms and while having other and more general 15 fields of usefulness is well adapted, and herein illustratively shown, for controlling the operative elements of an eyeleting machine to feed the material and space the eyelets. A prime object of the invention is to provide 20 a simplified, convenient and compact mechanism whereby the extent of an automatic feed can be variably set at minimum ranges and then without necessarily stopping the machine the extent of such automatic feed instantly shifted to a predetermined 25 variable maximum feed, or vice versa. To this end in the preferred embodiment herein shown I provide a cam member having 30 operating surfaces presenting operative circuits of different contour adapted to variably move an operated element in engagement therewith according to the operative circuit on said cam which it traverses. In accordance with a further feature 35 of the invention, means is provided whereby the operated element coöperative with the cam may be shifted while the mechanism is in operation to bring it opposite and in operative relation to different operative 40 circuits of said cam for variable actuation thereby, along with means whereby the limits of adjusting movement of said operated member may be varied as required to determine operative circuits of maximum 45 and minimum movement respectively. The above and other objects and features of the invention will be better understood from the following detailed description taken in connection with the accompanying drawings 50 and will be thereafter pointed out in the appended claims.

Referring to the drawings:

Figure 1 is a side elevation with parts broken away showing an illustrative embodiment of my invention;

Fig. 2 is a plan view thereof taken in section on line 2—2 of Fig. 1; and

Figs. 3, 4 and 5 are sectional details of the operating cam taken on section lines, 3—3, 4—4, and 5—5 respectively of Fig. 1.

The mechanism to be operated and controlled as herein illustratively shown is a pair of oppositely mounted eyeleting devices 1, 2, coöperative with a material support 3 disposed therebetween. These eyeleting devices are carried at the ends of levers 4, 5 having a journal mounting at 6 for movement toward and from the material support 3, herein shown as in a vertical direction. The levers 4, 5 and their journal bearing 6 are carried in a block 7 pivoted at its ends on the pointed pins 8, 9 to turn in a direction transverse to the swing of levers 4, 5 or as shown horizontally. The pivot pins 8, 9 are shown as carried in arms 75 projecting from a suitable supporting frame 10. The levers 4, 5 have at their inner portions rolls 11, 12 respectively adapted to be acted on, the one by a cam 13 and the other by a cam 14, these being wide peripheral 80 cams mounted side by side on a shaft 15 suitably journaled in the frame work. The rolls 11, 12 are held pressed against their respective cams by a tension spring 16 fixed at its ends to the respective lever ends. It 85 is required that the eyeleting devices 1, 2 be moved laterally back and forth to feed the material in addition to their endwise movement and for this purpose the levers 4, 5 are given a controlled swinging movement, the block 7 turning on the pivot pins 8, 9.

In accordance with my invention this feeding movement is effected by a cam having an operating face presenting a series of operative circuits of different contour which may be selectively engaged by a member carried with the operated mechanism, *e. g.*, the eyeleting devices. This cam is shown as a lateral face cam 17 also fixed on the shaft 100 15 and which may be formed in one with the peripheral cam 13. This cam is shown with an operating rise 18 at one side extending around to an opposite descent 19 for giving reciprocating movement to roll 20 which 105 rides thereon. By reference especially to the sectional views, Figs. 3, 4 and 5, it will be seen that the contour of the raised or outwardly projecting cam portion between the rise 18 and the descent 19 is not uniform 110

radially of the cam disk but slopes from a relatively low peripheral portion 21 to a relatively high or more projected portion 22 near the center of the cam disk, thus presenting a series of operative circuits for the roll 20 as the cam rotates, adapted to act variably on the roll for shifting it and the operated elements such as the eyeleting devices shown, by variable amounts according 5 to whether said roll is near the periphery or nearer the center of the face of the cam disk. It will be noted that this lateral cam presents at one side a flat neutral portion 220 which extends in from the periphery to 10 the extent of the limit of adjustment of the roll 20 and this flat portion which thus determines one limit of feed movement of the working mechanism, *e. g.*, the eyeleting devices, causes this limit to be fixed, whatever 15 20 may be the other limit of the variable movement as effected by the radial adjustment of the roll 20. This is of importance for permitting the working movement of the working mechanism at this point so that such 25 working movement is always effected at the same point, *i. e.*, at such fixed limit of the feed movement whatever may be the variably adjusted extent of such feed movement; thus the punch and set of an eyeleting 30 mechanism will be properly positioned with reference to the stationary punch block and clenching surface whatever may be the extent of lateral throw of such punch and set between working movements for effecting 35 the feeding. The roll 20 is shown as carried on a journal post 23 slidably fitted in a sleeve bracket 24 fixed to the journal block 7. A spring 25 fixed at one end to the frame work and at its other end to a projection 26 40 from the post 23 holds the roll 20 in engagement with the lateral cam face. The roll 20 is normally held at an outer limit of movement by a spring 27 pressing upon the end of post 23 and housed in the sleeve block 45 24 with a backing in the same. I provide means whereby the roll 20 may be moved from its outer position and held to traverse a predetermined operative circuit of the cam 17. For this purpose a bell crank lever 28 50 55 is fulerumed at 29 on the post 7 with one arm 28' pivotally engaged at 30 with the post 23 through a slot 31 in sleeve 24, the other arm 28'' of said bell crank lever extending out horizontally with a link connection 30 which may lead to an operating treadle (not shown). In accordance with my invention means is provided whereby the inner limit of movement of the roll 20 and also its outer limit of movement on the 60 65 cam face 19 may be varied as desired and for this purpose I provide for engagement with the lever arm 28'' upper and lower stops 32, 33 shown as eccentrics mounted to turn on bearings 34. These eccentrics are 70 75 80 85 90 95 100 105 110 115 120 125 130 shown as equipped with a series of spaced

apart notches 35 engageable by spring detents 36 to hold them yieldingly in any adjusted position to which they may be set. Thus both eccentric stops are as shown adapted to permit the maximum range of adjustment of the roll 20, *i. e.*, by drawing down on the link 30 the feed imparted to the eyeleting devices 1, 2 may be instantly changed from the minimum of which the machine is capable to the maximum. If it 70 be desired to vary said minimum feed, *e. g.*, to change from an eyelet spacing of, say three-eighths to one of seven-sixteenths inch, the upper eccentric stop 32 may be turned around from the position shown to another 75 position which may be graduated to indicate the desired change of feed, the eccentric stop in this new position limiting the upper movement of the arm 28'' and hence causing the roll 20 to occupy a position farther in on 80 the cam face 19 where it will engage an operative circuit with a higher or more projected cam rise. It will be understood that from such new position the roll may be shifted to instantly change the feed to the 85 maximum as before, by pressing down on the link 30, and if it be desired to vary the maximum feed obtainable by moving down the link 30 this may be quickly effected by turning the lower eccentric stop 33 to a new 90 95 100 105 110 115 120 125 130 adjusted position where it will limit the downward movement of the arm 28'' and hence limit the inward adjustment of roll 20 so that it will not engage so high a portion of the cam in its operative circuit as before. It is to be understood that the particular provision shown for variably limiting the range of adjustment of the operated element, *i. e.*, the roll 20, and consisting in the present embodiment in the eccentrics 105 32, 33 is merely illustrative, as is also the construction of bell crank lever 28, and spring pressed post 23 for their purpose, all these elements in a broader aspect of the invention being intended merely to typify any suitable means for effecting the adjustment of the operated member and varying one or both limits of such adjustment so that it will traverse selected operative circuits adapted to actuate it to a predetermined extent variable as required.

While the invention in its broader aspects is in no wise limited to such use, it is well adapted for use in eyeleting machines where the lower line of eyelets proper may be positioned the desired distance apart by properly setting the variable minimum feed, and then by merely pressing down the treadle lever as far as it will go as determined by the adjustment of the lower eccentric stop, 125 the roll 20 will traverse an operative circuit on the face cam that will produce a larger feed movement at each stroke as required for the spacing of the line of hooks in the upper of the shoe. I am aware that the in- 130

vention can be embodied in other specific forms without departing from the spirit thereof and I therefore desire the present embodiment as to details of construction, as well as to the use herein suggested, to be considered as illustrative and not restrictive, referring rather to the appended claims to indicate the scope of the invention.

Having described my invention, what I claim as new and desire to secure by Letters Patent is:

1. A variable feed mechanism, comprising a cam mounted for rotation and formed to present operative circuits of different contour for variably moving an operated member according to the circuit traversed thereby, an operated member, said cam and said operated member being relatively adjustable for the cam to present its different operative circuits to said member, at will, and working mechanism connected to said operated member to have feed movement imparted thereto by said operated member and having means for imparting working movement thereto at one limit of such feed movement, said cam being formed with a neutral flat portion controlling said operated member at said limit of feed movement whereby said limit of movement at which said working mechanism operates is invariable throughout the adjustment of said operated member.

2. A variable feed mechanism, comprising a cam, a member to be operated thereby for actuating a member to be fed, said cam and said operated member having mountings for relative operative movement, and also for relative adjustment for said member to traverse different operative circuits of said cam, said cam being formed so that it presents a series of operative circuits of different contour adapted to variably move said operated member, and working mechanism connected to said operated member to have feed movement imparted thereto by said operated member and having means for imparting working movement thereto at one limit of such feed movement, said cam being formed with a neutral flat portion controlling said operated member at said limit of feed movement whereby said limit of movement at which said working mechanism operates is invariable throughout the adjustment of said operated member.

3. A variable feed mechanism, comprising a lateral face cam mounted for rotation having a contour projecting at different distances from its periphery toward its center, an operated member mounted in position to be moved by said cam, means for moving said operated member radially of said cam to vary the extent of its operative movement, and working mechanism connected to said operated member to have feed movement imparted thereto by said operated member and having means for imparting working

movement thereto at one limit of such feed movement, said cam being formed with a neutral flat portion controlling said operated member at said limit of feed movement whereby said limit of movement at which said working mechanism operates is invariable throughout the adjustment of said operated member.

4. A variable feed mechanism, comprising a rotatable cam having portions adapted to present different operative circuits of varying contour to a member to be operated thereby for variably actuating said member, a member mounted in operative relation to said cam, means for adjusting said member to co-act with different operative circuits of said cam for variable actuation thereby, means for varying the limits of adjustment of said member for the purpose stated, and working mechanism connected to said operated member to have feed movement imparted thereto by said operated member and having means for imparting working movement thereto at one limit of such feed movement, said cam being formed with a neutral flat portion controlling said operated member at said limit of feed movement whereby said limit of movement at which said working mechanism operates is invariable throughout the adjustment of said operated member.

5. A variable feed mechanism, comprising an element to be moved for feeding purposes, a cam for moving said element intermittently and automatically, means for varying the position of said element with respect to said cam to vary the extent of such movement for feeding, means for adjustably limiting the extent of such variation, and working mechanism connected to have feeding movement imparted thereto by said element, and having also means for imparting working movements thereto at one limit of such feed movement, said cam having a flat neutral portion operative on said element at such limit of movement of a nature such that said limit is invariable throughout the variation of the extent of feed, so that said working movement is always at the same point.

6. A variable feed mechanism, comprising an element to be moved for feeding purposes, means for moving said element intermittently and automatically, means for varying the extent of such movement, means for adjustably limiting the extent of such variation at both the maximum and minimum limits of feed movement, and working mechanism connected to have feeding movement imparted thereto by said element and having also means for imparting working movements thereto at one limit of such feed movement, said element moving means constructed and arranged to return said element to the same position at one limit of

movement thereof throughout the variations in the extent of feed movement, so that said working movement is always at the same point.

- 5 7. A variable feed mechanism, comprising a rotatable lateral face cam having an operative projecting portion varying in degree of projection from its periphery toward its center, an operated member mounted in position to be actuated by said cam and also for adjustment radially thereof to vary the extent of its actuation, means for adjustably limiting the adjustment of said member in both directions to vary both the maximum 10 and minimum limits of movement thereof, and working mechanism connected to said operated member to have feed movement imparted thereto by said operated member and having means for imparting working movement thereto at one limit of such feed movement, said cam being formed with a neutral flat portion controlling said operated member at said limit of feed movement whereby said limit of movement at which said working mechanism operates is invariable throughout the adjustment of said operated member.

8. Apparatus of the kind described, com-

prising eyeleting mechanism, means for imparting feed movements to said mechanism consisting in a rotatable cam presenting a series of operative circuits with different degrees of operative projection, and with a flat neutral portion common to all operative circuits, an element connected with said eyeleting mechanism for engagement with said cam, means for adjusting said element to traverse different circuits of said cam for varying the feed movement, with means for varying the limits of such adjustment, and means for imparting operative movements to said eyeleting mechanism connected to be operated in timed relation to said feed movements at the limit of such feed movement determined by said neutral cam portion whereby said operative movements are always at the same point regardless of the extent of feed movement.

In testimony whereof, I have signed my name to this specification in the presence of two subscribing witnesses.

FRANK L. HARMON.
